UNITED STATES PATENT OFFICE.

EDWARD F. WILLIAMS, OF GRAIN VALLEY, MISSOURI.

ENTRANCE FOR STOCK-YARD PENS.

1,172,653.

Specification of Letters Patent.

Patented Feb. 22, 1916.

Application filed August 14, 1915. Serial No. 45,509.

To all whom it may concern:

Be it known that I, EDWARD F. WILLIAMS, a citizen of the United States, residing at Grain Valley, in the county of Jackson and State of Missouri, have invented certain new and useful Improvements in Entrances for Stock-Yard Pens, of which the following is a specification.

My invention relates to new and useful improvements in stock pens and more particularly to entrances therefor, the primary object of my invention being the provision of an entrance-way for stock pens of such a nature as to require no doors or closures and so arranged as to absolutely prevent passage of stock through the entrance, although at the same time permitting men to pass readily in and out of the pen.

A still further object of my invention is to provide an entrance-way of the above described character which may be employed not only to permit the passage of men into and out of the pen but which may be utilized as a passage-way between different sections of a pen and so arranged that two of the entrance-ways may be provided at adjacent corners of four pen sections to permit passage from any pen section into any other.

With these and other objects in view, my invention will be more fully described, illustrated in the accompanying drawings, and then specifically pointed out in the claim which is attached to and forms a part of this application.

In the drawings: Figure 1 is a top plan view of a pen of conventional type provided with my improved entrances; Fig. 2 is a front elevational view of the pen, both figures being upon a very much reduced scale.

Corresponding and like parts are referred to in the following description and indicated in all the views of the drawings by the same reference characters.

For the sake of clearness I have illustrated my entrances in connection with a conventional form of pen 10 which may be of any desired shape and size, the pen shown in the drawings being rectangular and including walls 11 secured to and supported by posts 12. These walls may be formed of rails, planks, wire or other suitable material or any combination thereof. For instance, in the drawings I have illustrated the walls as consisting, at their base, of planks 13 in or-

der to prevent escape of smaller stock and above such lower portion, of rails 14. In any event, the wall of the pen is usually approximately six feet high. The pen illustrated further includes a plurality of partition walls 15 dividing it into a plurality of sections or inclosures, these partition walls being constructed in the same manner as the outer walls of the pen and supported by posts 16. The outer wall of the pen is provided with gates 17 through which the stock may be admitted to the pen, at least one gate being provided for each inclosure of the pen, these gates being of the usual or any preferred construction. With the pens now in use, in order for a man to enter the pen it is either necessary for him to open one of these gates, which are usually large and through which some of the penned in animals may escape during his entrance, or to climb over the wall of the pen, a difficult and sometimes dangerous task. Furthermore, if the stock gates are opened, the man, when shutting them after him, may fail to lock them and so permit escape of the animals in the pen. Again, if the animals in the pen are unruly and attack the man while he is in the pen, it is almost impossible for him to escape through the door or gate, which must be first opened. My invention aims to overcome these difficulties by providing an entrance-way requiring no gate or movable part and so formed as to permit a man to pass easily through it and at the same time to prevent passage of the inclosed stock. In accomplishing this, I form the outer wall with entrance openings 18, one for each inclosure of the pen, these openings being approximately from 18 to 24 inches in width. Directly inside of these openings and at a distance of approximately 18 to 24 inches from the inner face of the wall, I erect a barrier 19 which extends parallel to the wall and which is preferably the same height or a little higher than the wall. This barrier is constructed of planks or other suitable material secured to posts 20, the posts being preferably secured to the inner face of the barrier in order that any pressure exerted against the barrier from within the inclosure will not tend to force the planks or other material making up the barrier from the posts.

Irrespective of the material of which the barrier is made, it should be solid in order

- that the stock inclosed in the pen may not be able to see through it and it should be so constructed that its ends will extend equally beyond the ends of the entrance openings 18.
- 5 As will be clear from an inspection of Fig. 1 of the drawings, a man may readily pass between one end of the barrier and the wall of the pen until he reaches the opening 18 in the wall and then pass from the pen. At 10 the same time, because of the reduced width of the opening 18 and the space between the wall and barrier, it is impossible for stock to escape as they cannot make the abrupt turns necessary in such limited space.
- 15 Passageways or entrances, similar to those above described, may be provided in any suitable points in the division walls 15 of the pen, but preferably I locate entrances in the division walls, as shown in Fig. 1.
- 20 As illustrated in this figure, all intersecting division walls, at their inner ends, stop in spaced relation to each other, the space between adjacent ends of the division walls being substantially from 18 to 24 inches. Barriers 21 and 22 are provided, extending across the space in one of the intersecting walls and at right angles to and against the adjacent ends of the other intersecting wall. By this means, I provide an entrance which 25 will permit a man in any pen to walk into any adjacent pen through the same entrance way and which will, nevertheless, prevent

passage of stock from one inclosure of the pen to another.

In view of the above different manners of 35 positioning the entrances, according to circumstances, it will be understood that I do not wish to be limited to any specific positioning of the entrances with respect to the walls of the pen or with respect to each 40 other, my invention consisting rather in the provision of an entrance-way in the wall of an inclosure of relatively narrow width and in the provision of a barrier in parallel spaced relation to such wall and projecting 45 at its ends beyond the sides of the opening therein.

Having thus described the invention, what is claimed as new is:

The combination with an inclosure, of a 50 partition wall, formed intermediate its length with a relatively narrow opening, barriers parallel to and slightly spaced from the partition wall, one at either side thereof and opposite the opening, with their ends 55 projecting materially beyond the sides of the opening, and partition wall sections connecting at their inner ends with the intermediate portions of the barriers, whereby passageways are furnished from any one of 60 the subdivisions of the inclosure formed by the partition walls into all others.

In testimony whereof I affix my signature.
EDWARD F. WILLIAMS. [L. S.]
